US0D1083458S

(12) **United States Design Patent** (10) **Patent No.:** **US D1,083,458 S**
(45) **Date of Patent:** **** Jul. 15, 2025**

(54) **DISPLAY STAND**

(71) Applicant: **All Plastic, Inc.**, Rancho Cordova, CA (US)

(72) Inventors: **William Thomas Smith**, Fair Oaks, CA (US); **Cheryl Ann Smith**, Fair Oaks, CA (US)

(73) Assignee: **All Plastic, Inc.**, Rancho Cordova, CA (US)

(**) Term: **15 Years**

(21) Appl. No.: **29/835,741**

(22) Filed: **Apr. 21, 2022**

Related U.S. Application Data

(60) Continuation of application No. 29/717,541, filed on Dec. 18, 2019, now Pat. No. Des. 953,075, which is a division of application No. 29/668,887, filed on Nov. 2, 2018, now Pat. No. Des. 878,120.

CLAIM

The ornamental design for a display stand as shown and described.

DESCRIPTION

FIG. 1 is a perspective view of a display stand in accordance with a first variant of our Design;

FIG. 2 is a top plan view of the display stand shown in FIG. 1;

FIG. 3 is a bottom plan view of the display stand shown in FIG. 1;

FIG. 4 is a left side view of the display stand shown in FIG. 1;

FIG. 5 is a right side view of the display stand shown in FIG. 1;

FIG. 6 is a front view of the display stand shown in FIG. 1; FIG. 7 is a rear view of the display stand shown in FIG. 1; FIG. 8 is a further perspective view of the display stand shown in FIG. 1;

FIG. 9 is a perspective view of a display stand in accordance with a second variant of our Design;

FIG. 10 is a top plan view of the display stand shown in FIG. 9;

FIG. 11 is a bottom plan view of the display stand shown in FIG. 9;

FIG. 12 is a left side view of the display stand shown in FIG. 9;

FIG. 13 is a right side view of the display stand shown in FIG. 9;

FIG. 14 is a front view of the display stand shown in FIG. 9;

FIG. 15 is a rear view of the display stand shown in FIG. 9; and,

FIG. 16 is a further perspective view of the display stand shown in FIG. 9.

The broken lines shown in the drawings show environmental subject matter and form no part of the claimed design. The shade lines in the drawings show contour and not surface ornamentation. The oblique line shadings in the drawings show a transparent surface and not surface ornamentation.
